STOCK GAUGE FOR BLAST FURNACES

Filed Aug. 21, 1947

UNITED STATES PATENT OFFICE

2,538,312

STOCK GAUGE FOR BLAST FURNACES

James Eric Heyworth and Edward Francis Har-
kins, Cleveland, Ohio, assignors to Republic
Steel Corporation, Cleveland, Ohio, a corpora-
tion of New Jersey

Application August 21, 1947, Serial No. 769,924

5 Claims. (Cl. 33—126.5)

1

This invention relates to a new stock gauge assembly for a blast furnace, particularly a furnace operating at gas pressures which are higher than conventional pressures.

Stock gauges which are used to determine the stock line or location of the top surface of the charge or burden in the blast furnace are subjected to severe service conditions. Solids carried by the gases in the furnace chamber impinge against the cables or rods and tend to erode or abrade them. Also, when charging, the solid materials discharged from the charging hopper into the furnace may strike and damage the gauge. Furthermore, the gauge must be capable of being moved up and down through the top of the furnace and yet must be sealed against the escape of gases. The problem of providing a satisfactory stock gauge has always been present, even with furnaces operating at conventional pressures, but is acute with furnaces operating at higher than conventional pressures. In higher pressure operations the pressure drop through the packing of the stock gauge is greater than in conventional operations, and consequently gas escaping through the packing would flow more rapidly and cause substantially more than normal erosion.

The present invention provides a stock gauge which has satisfactorily met the conditions of high pressure furnace operation. Briefly described, this gauge comprises a cable carrying a weight at its lower end in the furnace and extending up through the top of the furnace within a tube. In its preferred form the cable is equipped with a tubular protector consisting of short lengths of pipe loosely surrounding the cable. Guides are positioned in the tube some distance apart and substantially fill the space between the inner surface of the tube and the outer surface of the cable, or its tubular protector when a protector is present. The tube is provided with an inlet between the guides for gases under greater pressure than that in the furnace. Thus the flexible cable is protected against erosion and abrasion, the escape of gas from the furnace is impeded by the guides and higher pressure gas, and the higher pressure greatly retards, if not prevents the entry of abrasive solids into the tube.

A better understanding of my invention will be gained by those skilled in the art upon consideration of the following detailed description and the drawings accompanying and forming a part of this specification, in which

Figure 1 is a fragmentary, side elevational view,

2

partly in section, of stock gauge assembly embodying one form of this invention:

Figure 2 is an enlarged fragmentary view of a portion of the gauge assembly of Fig. 1 taken on line 2—2 of Fig. 3 and showing the gas pressure chamber; and

Figure 3 is a cross sectional view taken on line 3—3 of Fig. 2.

The present stock gauge comprises a cable 10 which is secured at one end to a weight 11 to maintain constant tension in the cable, and at the other end to a winch (not shown) for raising and lowering the cable and weight to determine the stock level within a blast furnace.

As illustrated in Fig. 1, cable 10 extends vertically through dome 12 of the blast furnace and through an upright housing 13 secured to the dome and fitted with a removable apertured closure plate 14 at its upper end outside the furnace.

Throughout most of its length, including that part normally within the furnace, cable 10 is provided with protecting sleeves 16 made up of a plurality of short pipe sections which are supported by a retaining ring 17 secured to cable 10 above the point of attachment of weight 11. Above housing 13, the cable and sleeves 16 are enclosed in a vertically extending gas sealing chamber 20 through which the cable and sleeves may move freely when determining the stock level in the stack of the furnace.

Chamber 20 is defined by a tube 21 having open ends, and an opening at an intermediate point communicating through a pipe or conduit 23 with a source of gas under pressure (not shown). Two centrally apertured guides or bushings 24 are welded to the ends of the tube 21. An auxiliary pipe 25 opens upwardly into tube 21 near the upper bushing.

The guides 24 are preferably of larger outside diameter than the tube 21, and the central apertures in these guides are flared outwardly so that the ends of the tube 21 may be seated therein and welded to the guides, as shown in Fig. 2. Between the flared ends, the apertures are of slightly greater diameter than the outside diameter of sleeves 16, so that gas flow into or out of the chamber through the guides will be impeded, yet will permit free vertical movement of the sleeves and cable through chamber 20. The lower guide 24 may be welded to plate 14, with the apertures in the guide on the plate in register.

The lower guide or bushing 24 is provided with a plurality of, in this case three, passages 26 inclined downwardly therethrough and opening into the central aperture thereof. Pipes 27 are welded

to the bushing and communicate with passages 28.

In the use of the illustrated device, gas is injected continuously through pipe 23 into chamber 20 at a predetermined pressure slightly in excess of that prevailing in the upper portion of the furnace. In this manner, there is constant flow of the gas through the upper guide 24 to the atmosphere, and ordinarily through the lower guide 24 into the furnace chamber. Under certain circumstances there may be substantially no flow through the lower guide from the chamber to the furnace, however it is preferable to maintain the pressure within the chamber so that little or no furnace gas is permitted to flow into the sealing chamber.

Steam has been found suitable for pressurizing chamber 20, since leakage of steam through the lower guide 24 into the furnace is not harmful or detrimental to the structure or operation of the furnace or to the various parts of the gauge assembly, especially where the chamber pressure is in the order of 1 to 2 pounds per square inch greater than the pressure in the adjoining part of the furnace. Steam may be blown through pipe 25 to aid in cleaning out any solids which may have collected in upper bushing 24, and may be blown through pipes 27 similarly to clear away solids in the lower bushing. Other gases may, of course, be used, and likewise other parts and combinations of parts than those herein illustrated may be used without departing from the spirit of this invention or the scope of the appended claims.

Having thus described the present invention so that those skilled in the art may be able to practice and understand the same, we state that what we desire to secure by Letters Patent is defined in what is claimed.

What is claimed is:

1. A blast furnace stock gauge comprising a cable, a protector for the cable comprising short lengths of pipe around the cable, a tube through which the cable extends, stationary guides disposed at spaced apart places in said tube and substantially filling the spaces between the inner surface of the tube and the outer surface of the cable protector, and means between said guides for admitting gas under pressure into the interior of the tube.

2. A blast furnace stock gauge comprising a cable, a protector for the cable comprising a pipe through which the cable extends, a tube through which the cable and pipe extend, a pair of spaced stationary guides secured to the tube and each

having a portion of inside diameter substantially less than the inside diameter of said tube but greater than the outside diameter of the cable protector pipe and substantially the same diameter as the pipe, and means between said guides for admitting gas under pressure into the interior of the tube.

3. A blast furnace stock gauge comprising a vertical tube, guide bushings at each end of the tube, a cable extending through said bushings and tube and having a weight attached to its end within said furnace, a pipe communicating with the interior of said tube to supply gas under pressure to said tube, the lower bushing having a passage extending downwardly at an acute angle through the wall thereof, and a pipe connected to said bushing for conducting gas under pressure into said passage.

4. A blast furnace stock gauge comprising a vertical tube, guide bushings at each end of the tube, a cable extending through said bushings and tube and having a weight attached to its end within said furnace, a pipe communicating with the interior of said tube to supply gas under pressure to said tube, and a second pipe for gas under pressure opening at an acute angle into the said tube near the upper bushing.

5. A blast furnace stock gauge comprising a vertical tube, guide bushings at each end of the tube, a cable extending through said bushings and tube and having a weight attached to its end within said furnace, a pipe communicating with the interior of said tube to supply gas under pressure to said tube, a second pipe for gas under pressure opening at an acute angle into the said tube near the upper bushing, the lower bushing having a passageway extending downwardly at an acute angle through the wall thereof, and a pipe connected to said bushing for conducting gas under pressure into said passageway.
